LATHING MACHINE

John F. Buller, Dallas, Oreg.

Application September 25, 1940, Serial No. 358,373

5 Claims. (Cl. 72—128)

This invention relates to lathing machines and is particularly adapted for applying wooden laths to the studding of buildings to be lathed and plastered.

The primary object of the invention is to provide a holder for holding a number of laths in spaced relation with one another while nailing them to the studding.

A further object of the invention is to provide a lathing machine for holding the laths in spaced relation with one another while adjusting a holding clamp to the laths, said holding clamp having suitable mechanism therein for clamping the laths in spaced relation with one another and holding them while they are being nailed to the studding of the wall.

A still further object of my invention is to so build a lathing machine that can be folded up into a small space while not in use.

These and other incidental objects will be apparent in the drawings, specification and claims to follow:

Referring to the drawings:

Figure 1 is a perspective view of my new and improved lath holding rack, having laths stacked therein. This view also shows the holding clamp being applied to the upper layer of the laths which are to be applied to the studding of the building.

Figure 2 is a plan view of the lath holding rack.

Figure 3 is a side view of the holding rack in the process of being folded into a smaller space.

Figure 4 is a plan view looking down on the holding clamp, having laths clamped thereto.

Figure 5 is an inverted plan perspective view of the clamp.

Figure 6 is a sectional view, taken on line 6—6 of Figure 4, looking in the direction indicated, parts broken away for convenience of illustration.

Figure 7 is a fragmentary plan sectional view, taken on line 7—7 of Figure 6.

Figure 8 is a fragmentary sectional view, taken on line 8—8 of Figure 4.

Figure 9 is an inverted fragmentary sectional view of the holder as it is applied to the laths before the laths are locked in place.

Figure 10 is the same as Figure 9 after the laths have been locked in place.

In the drawings:

I will first describe the lath holding rack for stacking the laths, one upon the other, in spaced relation. The main frame for the holding rack is indicated by numeral 1 and is supported upon legs 2 and 3. The legs 2 are pivotally mounted to the frame at 4 and are held in upright position by 50

suitable brackets 5. The legs 2 are connected together by a cross bar 6 at their upper ends, having their lower ends mounted on the shaft 7, which is journaled within the rollers 8. Extending upwardly from the cross bar 6 is spacing bars 9 for separating the stacks of laths 10. The legs 3 are pivotally mounted at 11 to the main frame 1, and have a cross bar connection 12 at their upper ends upon which is mounted the spacer bars 13 for spacing the stacks of laths 10. The legs 3 are held in upright position by the braces 14. A header or guide 15 is pivotally mounted to the frame 1 at 16 and is held in a vertical upright position while the laths are being stacked, providing a stop for squaring up the stacks of laths.

My new and improved lath holding rack may be folded as illustrated in Figure 3, the legs 2 are pivotally mounted within the frame 1 and are folded in the direction indicated, while the legs 3 are pivotally connected to the outside of the frame 1 and fold in the direction indicated when the braces 5 and 14 are released from the frame as shown. The header 15 may also be folded in the direction illustrated after the legs 2 are folded. 20 This makes a compact package for porting from place to place. The end 17 of the frame 1 is extended, as shown, and provides a means of supporting the end of the frame, raising the legs 3 off the supporting surface allowing the operator 25 to transfer the location of the lath holding rack through the use of the rollers 8.

In the operation of my new and improved lath holding rack and laths are stacked upon the frame 1 between the spacing bars 9 and 13 and within 30 and against the header or guide 15. This arranges the stacks of laths so that my new and improved holding clamp 18 may be applied to the surface of the stack of laths clamping the laths thereunder so that they may be applied to the studding of the building being lathed.

The lath holding clamp consists of a main body portion 19 having guide bars 20 spaced therefrom by the bracket arms 21. Extending downwardly from the guide bars are spacing pins 22. These pins enter the spaces 23 between the laths 10 when the holding clamp is placed upon the stack of laths. Extending downwardly from the main body portion are locking bars 24. These bars are oblong in shape and pass down between the lath spaces 23 when parallel with the length of the laths. When these locking bars are in place between the laths and are revolved 90 degrees or less they will engage the edges of the laths cutting their way into the edge of the lath and holding the laths in place underneath the holding clamp.

Locking bars 22 have sharp points 25 for cutting into the edges of the laths when revolved so that their length is transverse the length of the lath. These locking bars are mounted to shafts 26, which are journaled within the main body portion 19 of the holding clamp. The upper ends of the shafts 26 have crank arms fixedly mounted thereto, having their opposite ends pivotally connected at 28 to the connecting link 29. The shaft 31 of one of the locking bars 24 extends upwardly through the main frame and has a handle 32 fixedly mounted thereon. When this handle is turned it will revolve the shaft 30 and the crank arm 27A shift the connecting link 29 to one side or the other at the same time revolving the other 15 cranks 27 through a range of 90 degrees rotating all of the locking bars 24 to either locked or unlocked position.

In the views 6 and 7, the locking bars are shown in locked position. The locking bars 24A 20 are operated on either end of the holding clamp are operated by the cam cranks 33 having their cam slots 34 coacting with the cam pin 35. The purpose of this construction relative to the end locking bars is to allow these bars to be located on the extreme 25 edge of the holding clamp and still provide sufficient rotation to the locking bars.

In the operation of my holding clamp, the clamp is applied to the stack of laths, as shown in Figure 1, the handle 32 is revolved to the position shown, engaging the locking bars between the edges of the laths and also the outer edge of the outer stack of laths gripping the laths in spaced relation to the underside of the holding clamp. The pins 22 hold all the laths in alignment. The holding clamp is next raised from the lath holding rack lifting the upper layer of laths with the same. The holder then is brought into the position where the laths will be brought in the proper position relative to the studding of the building. The locking bar 24A and the outer spacing pins 22 will rest on the upper lath that had formally been applied to the studding. The operator then rests his elbow against the holding clamp and applies a nail to the lath, fastening the lath to the studding, after he has nailed the laths

5 in place he removes the clamp by revolving the handle 32 so that the locking bars will be released from between the laths by revolving the longitudinal length parallel to the spacing of the laths.

I do not wish to be limited to the particular mechanical embodiment shown, described and claimed, as other mechanical equivalents may be substituted, still coming within the scope of the claims.

What is claimed as new is:

1. A lathing machine including, means for supporting a plurality of laths in proper nailing spacing, and a clamp for directly interlocking with the side edges of a plurality of said laths and holding them in proper relation to be applied to the studding for nailing.

2. A lathing machine including, uprights for supporting a plurality of laths in properly spaced relation for nailing, a clamp movable with respect to the uprights and adapted to be interlocked with the side edges of each of a plurality of laths to permit the laths to be raised from the uprights and applied to the studding.

3. A construction as defined in claim 2 where-in the clamp includes elements to be positioned between adjacent laths spaced by the uprights and operated to engage and hold such adjacent laths in fixed relation to the clamp.

4. A construction as defined in claim 2 where-in the clamp is provided with locking bars to be normally positioned between adjacent laths and free of engagement therewith, and means carried by the clamp to operate the locking bars to engage the edges of adjacent laths to fix the laths with respect to the clamp.

5. A construction as defined in claim 2 including a series of locking bars movably supported in the clamp and adapted respectively to inter-fit between adjacent laths, the edges of the locking bars being sharpened, and means on the clamp to turn the locking bars to cause their sharpened edges to bite into and support adjacent laths, when a series of laths is raised in the clamp.

JOHN F. BULLER.
